NOVELTY DESK SET

Harry Dearling, New York, and Edward Malan, Brooklyn, N. Y., assignors to Rubicon Inc., New York, N. Y., a corporation of New York

Application June 20, 1957, Serial No. 46,670

Term of patent 7 years

(Cl. D74—1)

The figure on the drawing is a side perspective view of a novelty desk set showing our new design. The desk set presents a similar appearance when viewed from the opposite side.

We claim:

The ornamental design for a novelty desk set, substantially as shown and described.
